UNITED STATES PATENT OFFICE.

ZENAS FETTERLY AND OSCAR DUTTON, OF YOLO, CALIFORNIA.

BARREL-TAP.

SPECIFICATION forming part of Letters Patent No. 234,377, dated November 9, 1880.
Application filed June 8, 1880. (No model.)

To all whom it may concern:

Be it known that we, ZENAS FETTERLY and OSCAR DUTTON, of the city and county of Yolo, in the State of California, have invented an 5 Improved Barrel-Tap; and we do hereby declare that the following is a full, clear and exact description thereof, reference being had to the accompanying drawings.

Our invention has reference to that class of 10 devices for drawing liquids from barrels and casks in which a tap-plug is permanently secured in the barrel-head, so that by securing a draw-pipe in a hole prepared for the purpose in the plug and turning a spigot in the tap 15 by means of a key the liquid is drawn through the pipe.

Our invention relates to the construction of 20 the tap and spigot; and it consists of a simple arrangement by which we secure a perfectly 25 tight joint through which leakage is impossible, and which will remain tight as long as the tap lasts.

It also relates to an attachment for cleaning 25 the inner end of the hollow spigot every time the spigot is turned, which is especially useful when the tap is used in beer-barrels that are pitched after being used.

Referring to the accompanying drawings, 30 Figure 1 is a perspective view with a side partly broken away. Fig. 2 is a longitudinal section through the outer shell or plug. Fig. 3 is an end view taken from the left-hand side of Fig. 2. Fig. 4 is a view taken from the right-hand side of Fig. 2. Fig. 5 shows details of the hollow conical spigot. Fig. 6 is a 35 longitudinal section through the outer shell, with the conical spigot removed.

Let A represent a hollow tapering metal plug or shell, the outer or large end of which is enlarged or flanged so as to form a head, b, while the exterior of the tapering portion is provided with screw-threads, so that it can be screwed into a hole in the head of the barrel until the under side of the flanged portion or head b fits 45 down against the outside of the barrel-head, leaving the small end of the plug to project inside of the barrel. We shall usually make the tapering threaded portion of the plug large enough to fit in the ordinary bung-hole in the 50 head of the barrel; but this is simply a conven-

ience and is not necessary, as it can be made of any desired size and a special hole bored for it.

A hole, h, is made in the outer end of the plug on one side of the central hole, in which 55 the spigot fits and operates, and this hole is either made angular or is curved, so as to connect with the interior bore of the plug. The outer portion of this hole is tapped with screw-threads, so that one end of a bent pipe, K, 60 can be screwed into it for drawing the liquid through.

The interior bore of the plug is tapering, being largest at the inner or small end and smallest at the outer end. In this tapering 65 bore we place the hollow tapering core or spigot C, which is ground to fit the taper of the bore, so as to form a joint that will keep tight as it wears. The lower end of this hollow core or spigot is covered by a plate which 70 is perforated, so that the liquid can pass to the interior of the spigot. The outer end of the spigot has a square or other shaped recess, S, in it, into which a key, T, will fit, in order to turn the spigot when desired.

A transverse slot, e, is made on each side of the spigot C, and a screw-bolt, f, passes through the plug and through the slots in the spigot, so that the spigot can be turned either way 80 as far as the slots and screw-bolt will permit.

A hole, g, is also made through the side of the hollow spigot in the same plane with the opening of the passage h in the plug, so that when the spigot is turned in one direction as far as the screw-bolt f and slots will permit 85 the two holes are brought opposite each other, and the liquid can pass from the hollow spigot out through the hole h and bent pipe K; but when the spigot is turned in the opposite direction the hole g is thrown out of line with 90 the passage h and the flow of liquid is cut off.

A bolt, l, is arranged in the wall of the bore near the outer end of the plug, so as to be thrown outward by a spring and enter a recess or socket, u, in the spigot when the spigot 95 is turned off, and thus lock it in place.

A slot, O, is made from the outer end of the spigot down in a line across the recess or opening u, and a wedge-plate, V, is secured on one side of the key T, so as to pass down 100

through this slot when the key is inserted into the outer end of the spigot and press the bolt *l* back out of the recess, and thus unlock the spigot and allow it to turn.

5 This forms a simple and effective faucet or permanent tap for beer and other barrels in which a liquid is contained under pressure. The conical spigot fits lengthwise in the shell, so that the pressure inside of the barrel keeps 10 the joint tight and prevents leakage. The device is cheaply constructed and durable, as the liquid-passage *h* is bored directly through the outer shell.

When not in use the key *T* is withdrawn 15 and the draw-pipe *K* removed, so that nothing projects from the end of the barrel except the shallow head *b*. The removal of the key permits the bolt *l* to enter the recess or socket *u* and lock the spigot in position.

20 In order to keep the inside end of the spigot clear, we secure a knife or scraper, *X*, across the inner end of the plug or shell *A*, so that when the spigot is turned to let on the liquid the edge of the knife or scraper will clear the 25 perforations or holes in the end plate, through which the liquid passes to enter the spigot. This knife or scraper is held in place by a transverse bar, *Y*, and screw *Z*. The end of the shell has an opening cut in each side opposite each other, and a groove, *a*, is made 30 around it on the inside, so that the ends of the bar can drop through the openings and be turned into the groove. The screw *Z* passes through its middle and bears against the middle of the knife or scraper, so that by turning 35 the screw against the back of the scraper the pressure of the scraper against the perforated

plate can be regulated. This provides an automatic cleaner that will keep the perforations clear, and is especially useful in beer-barrels 40 that are pitched after using.

Having thus described our invention, what we claim, and desire to secure by Letters Patent, is—

1. An improved tapping device for barrels 45 and casks containing liquid, consisting of the tapering exteriorly-threaded plug or shell *A*, having the head *b*, bore or hole *h*, draw-pipe *K*, and push-pin *l*, and provided with a smooth tapering bore, in combination with the hollow 50 spigot *C*, having the hole *g* in its side and key-hole *u* in its outer end, said spigot being secured in the hollow shell *A* by means of the opposite transverse slots *e* and screw-bolt *f*, combined and arranged substantially 55 as described.

2. In a barrel-tapping device having a rotary spigot operated by a removable key, the recess or socket *u* in the spigot and the bolt *l* in the plug or shell, in combination with the 60 slot *O* in the outer end of the spigot and the wedge-plate *V* on the key, substantially as and for the purpose specified.

3. In a barrel-tapping device having a rotary hollow spigot, into which the liquid is admitted through a perforated end, the stationary knife or scraper *X*, for the purpose specified. 65

In witness whereof we have hereunto set our hands and seals.

ZENAS FETTERLY. [L. S.]
OSCAR DUTTON. [L. S.]
